(57) **CLAIM**

The ornamental design for a packaging box, as shown and described.

DESCRIPTION

FIG. 1 is a perspective view of a packaging box showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the packaging box of FIG. 1 with the inner part of the packaging box partly pulled-out; and,

FIG. 10 is an exploded perspective view showing the packaging box of FIG. 1 in a disassembled orientation.

1 Claim, 10 Drawing Sheets
